UNITED STATES PATENT OFFICE

FRANCIS A. BARBEY, OF CAMBRIDGE, MASSACHUSETTS

BLOWER-NOZZLE PROTECTOR FOR FIRE BOXES

Application filed August 11, 1927. Serial No. 212,198.

This invention relates to a locomotive or other fire-box into which a fluid under pressure, such as steam or hot air, is projected by a blower whose terminal passes through an opening in a wall of the fire-box and is provided with an outlet arranged to project the fluid in a predetermined direction or directions.

The object of the invention is to provide a nozzle-terminal protector which includes a block molded from highly refractory non-metallic material such as fire clay, and is readily attachable to a fire-box wall and adapted to protect the major portion of the terminal from the fire, and at the same time permit the projection of fluid in the direction or directions desired.

Of the accompanying drawings forming a part of this application,—

20 Figure 1 shows in longitudinal section and somewhat conventionally, a locomotive fire-box, in a wall of which a blower nozzle is inserted, said wall being provided with a protector embodying the invention.

25 Figure 2 is a fragmentary perspective view, showing portions of the wall and nozzle, and showing the protector block seated on the wall and operatively related to the nozzle.

Figure 3 is a section on the plane indicated 30 by line 3—3 of Figure 2.

Figure 4 shows the protector block in section as shown by Figure 3.

Figure 5 is a view similar to Figure 3, the 35 protecting filling hereinafter described being omitted.

The same reference characters indicate the same parts in all of the figures.

In the drawings, 12 designates a portion of a side wall of a fire-box, the fuel bed of 40 which is designated by 13. 14 designates a pipe which may communicate with a source of supply of steam, or hot air under pressure, and has a nozzle 15 projecting through an opening 16, formed for its reception in the wall portion 12. The nozzle projects into the fire-box and has an outlet which may be formed by one or more ports 17, the outlet being arranged to project fluid in a predetermined direction or directions into the fire-box above the fuel bed. In a locomotive fire-

box the wall portion 12 may constitute the inner side of a water leg, and the opening 16 may be the bore of a tube 18, connecting the wall portion 12 with an outer wall portion (not shown) constituting the outer side 55 of the water leg.

Clamped against the inner side of the wall portion 12 is a refractory block 19 of hardened fire-brick material having an inner end face 20, seated on said wall portion, a front side face 20^a, provided with a recess 21, formed to receive a portion of the nozzle 15 and expose the outlet thereof, an outer end face 20^b, spaced from an end of the recess, and a rear side face 20^c, spaced from the bottom of the recess. The block is provided with elongated bolt-receiving orifices 24, extending from the inner end face 20 to the outer end face 20^b, and between the bottom of the recess 21 and the rear side face 20^c, said 60 orifices having enlargements 25 at their outer ends providing nut abutments 26, and formed to receive portecting fillings 30 of fire-brick material inserted while plastic, and subsequently hardened.

Fixed to and projecting inwardly from the wall portion 12, are metal bolts, or studs 23, of which there may be two, as indicated by Figure 1. The inner ends of the bolts are threaded and screwed into tapped sockets 70 in the wall portion 12, and extend into the orifices 24. The outer ends of the bolts are threaded, and with these threaded ends are engaged clamping nuts 27, cooperating with the abutments 26, in clamping the inner end 75 face 20 against the wall portion 12.

As shown by Figure 1, the block is adapted to be interposed between the major portion of the nozzle 15, and the fuel bed 13, so that 80 injury to the nozzle by heat is prevented, the nozzle being sufficiently exposed to permit it to project fluid away from the block.

The block in the condition shown by Figure 4, is placed on the studs whose threaded ends project into the enlargements 25. The 85 nuts 27 are then applied and screwed to a firm bearing on the abutments 26, washers 28 being preferably interposed between the nuts and abutments. After the block has been 90 thus fixed to the wall, the fillings 30 are in- 95

serted in the enlargements 25 and allowed to solidify therein, so that they protect the outer ends of the studs and the nuts.

The block if cracked or broken, can be readily removed and a new one substituted for it, the nuts 27 being first removed. The fire-box wall requires no adaptation other than the formation of tapped sockets therein, for the reception of the inner ends of the studs. It is therefore a simple matter to secure a protector to a fire-box wall in accordance with my invention. The protector enables the nozzle to remain continuously in the fire-box for a long period, without being burned out.

I claim:

1. A blower nozzle-protecting attachment for a fire-box having in a wall portion thereof a blower-receiving opening, said attachment comprising a nozzle-protecting block of fire-brick material, having an inner end face seated on said wall portion, a front side face provided with a recess formed to receive a portion of a blower nozzle extending through said wall opening, an outer end face spaced from an end of said recess, and a rear side face spaced from the bottom of the recess, the block being provided with elongated bolt-receiving orifices extending from the inner to the outer end face, and between the bottom of the recess and the rear side face, said orifices having enlargements at their outer ends providing nut abutments and formed to receive nut-protecting fillings, bolts engaged with tapped sockets in said wall portion, and extending into said orifices, clamping nuts engaged with the outer ends of the bolts and cooperating with said abutments, and fillings of refractory material inserted in the enlarged ends of said orifices and protecting said nuts.

2. A blower nozzle-protecting block of fire-brick material, having an inner end face formed to be seated on a wall portion of a fire-box adjacent a blower nozzle extending through said wall portion, a front side face provided with a recess formed to receive a portion of said nozzle, an outer end face spaced from an end of said recess, and a rear side face spaced from the bottom of the recess, the block being provided with elongated bolt-receiving orifices extending from the inner to the outer end face and between the bottom of the recess and the rear side face, said orifices having enlargements at their outer ends providing nut abutments and formed to receive protecting fillings.

In testimony whereof I have affixed my signature.

FRANCIS A. BARBEY.
